UNITED STATES PATENT OFFICE.

BARTHolemew F. KLOHS, OF CANTON, OHIO, ASSIGNOR TO THE DIEBOLD SAFE & LOCK COMPANY, OF CANTON, OHIO, A CORPORATION OF OHIO.

BOLT-OPERATING MECHANISM FOR SAFE-DOORS.

1,118,426.

Specification of Letters Patent.

Patented Nov. 24, 1914.

Application filed December 23, 1909. Serial No. 534,701.

To all whom it may concern:

Be it known that I, BARTHolemew F. KLOHS, a citizen of the United States, residing at Canton, in the county of Stark and State of Ohio, have invented certain new and useful Improvements in Bolt-Operating Mechanism for Safe-Doors, of which the following is a specification.

My invention relates more specifically to the setting of the mechanism designed to actuate the lock bolts by the rotation of the door when in a closed position.

The object of the invention is to provide means whereby the bolt releasing device may be actuated by the energy stored in the springs when compressed.

I attain the object mentioned, together with other objects which will be apparent to those skilled in the art by the construction illustrated in the accompanying drawing, in which—

Figure 1 is a vertical section through a portion of the safe door, illustrating a side view of the spring case, the time lock and case removed and illustrating the lock bars in position to be actuated by the rotary movement of the door. Fig. 2 is a horizontal section of the door, showing a portion of the safe and illustrating the door closed, also showing an edge view of the lock plate and the parts carried by the said plate. Fig. 3 is a view showing a portion of the lock case and cover plate with relation to the door showing the position of the bendable plate or sheet and the lug to prevent movement of the lock bars. Fig. 4 is a detached perspective view of the spring setting lever, its shank and setting key. Fig. 5 is a vertical section of the door showing the door closed and unlocked and illustrating the lock plate and the device carried by said lock plate. Fig. 6 is a similar view showing the door locked. Fig. 7 is a rear side elevation of the lock plate and spring case showing the cover plate removed and illustrating the door proper in a locked position the parts being shown on a larger scale. Fig. 8 is a rear side elevation of the spring case showing the lock plate removed and illustrating the springs in a released position. Fig. 9 is a similar view showing the springs compressed illustrating the relation of the parts before the lock bar is opened or released. Fig. 10 is a rear side elevation of the lock plate and spring case, showing the cover plate removed and illustrating the door proper in an unlocked position the parts being shown on a larger scale. Fig. 11 is a view similar to Fig. 9 and illustrating the parts in proper relationship when the lock bar is in a released position. Fig. 12 is a detached perspective view of the lock bolt releasing head. Fig. 13 is a detached perspective view of the latch holding lever.

Similar numerals of reference indicate corresponding parts in all the figures of the drawings.

In the accompanying drawing, 1 represents a portion of a safe which is of the usual construction and has within itself no specific reference to the present invention. The safe 1 is provided with the usual door opening, which in this instance is circular and in which opening the door 2 is to be entered and closes the safe in the usual manner. The door 2 is suspended upon a hinged yoke of the usual construction and so connected that the door can be rotated axially. The yoke is not illustrated as it does not have any specific reference to the present invention. The periphery of the door is provided with a series of lugs or extended flanges 3 and the periphery of the door opening is also provided with a series of lugs or inward extending flanges, 4^a, which are so arranged with reference to each other that when the door is closed and rotated the lugs will interlock, thereby, providing means for securely locking the door against outward movement and at the same time necessitating the rotation of the door to bring it in position to be opened. These various lugs or extended flanges upon the door and the door jamb are of the usual construction and hence need no detailed description. The door 2 is provided with a chamber, 4, in which chamber the time lock and the bolt releasing mechanism, the springs and the various parts pertaining to the lock mechanism are located. It will be understood that within this chamber 4 is to be located the time locks designed to release the bolts at a predetermined time, which time locks are of the usual construction and form no specific part of the present invention. The lock plate 5 is formed of such a size that the various parts designed to be carried by said lock plate can be properly connected and arranged with reference to each other.

110

It is well understood that the lock plate 5 should be set in a true vertical position so that the various lock bolts will pass in and out without binding. Difficulty is sometimes experienced in setting the lock plate, and in order to overcome this difficulty I provide springs 6, the ends of which abut against the front wall of the chamber 4 and the front face of the lock plate 5, which 5 springs are located around the lock plate holding screws 7, which screws are entered in screw threaded apertures 8 formed in the door 2.

It will be understood that by providing 10 the springs 6 and locating the springs around the plate holding screws 7, that said springs can be compressed or released by turning the screws 7 in opposite directions, thereby providing means for truing up the 15 lock plate 5. It is well understood that in the manufacture of safes hard steel or like material is employed and by reason of this, much difficulty is experienced if filing must be done in order to true up the lock plate, 20 but by providing the springs 6 this difficulty is overcome. It will be understood that at places where screw threaded apertures are to be formed soft blocks of steel are cast in the door. This art, however, is old, and is 25 well understood by those skilled in the art.

To the lock plate 5 is securely attached the spring-case 9 by means of the screws 10. Within the spring-case 9 is located the cross head 11, which cross head is formed of a 30 length to correspond substantially with the spring case 9, but should be so formed that the cross head is free to move up and down for the purpose hereinafter described. Directly below the cross head 11 is located the 35 short bar 12 which is formed integral with cross head 11, which bar is for the purpose of providing means for elevating the cross head through the instrumentality of the setting lever 13, which lever is located or 40 formed integral with the shaft 14, which shaft is properly journaled in the flange 15 and the lock plate 5. The shaft 14 is provided with the angular extension or shank 16, which angular extension or shank is for 45 the purpose of providing a setting stem, upon which the key 17 is placed when it is desired to compress the springs 18 and 19. The springs 19 move the head 23 upward until it engages the T-head 22 located upon 50 the bar 21. For the purpose of reducing the frictional contact between the end of the bar 12 and the lever 13, said lever is provided with the anti-friction roller 20. From the cross head 11 extends the bar 21, which bar 55 is provided with the T-head 22, which T-head is for the purpose hereinafter described.

Upon the bar 21 is mounted the sliding head 23, which sliding head is substantially 60 of the form shown in Fig. 12 and as shown

it consists of two parallel blocks held in proper spaced relationship by means of the bridge bar 24. The sliding head 23 is guided by means of the flanges 25, said flanges being formed integral with the spring case 9. The bar 21 is located between the members of the head 23, which members form a guide for the movement of the bar 21.

The tie or bridge bar 24 is provided with the lug or flange 26, to which lug or flange 70 is pivotally attached the link 27, which link is pivotally attached to the disk 28, which disk is mounted upon the stud 29, which stud 75 may be formed integral with the lock plate 5 or it may be made separate and attached in any convenient and well known manner. To the disk 28 is pivotally attached the lock bolt actuating links 30, which links are formed substantially alike and are each connected to the lock bolts 31 and 32, which lock bolts reciprocate for the purpose of locking the door and releasing the door as 80 hereinafter described.

It will be understood that the links 30 and the lock bolts 31 and 32 are to be pivotally connected together by means of the pins 33, which pins are held in proper position by means of the integral screw threaded portions 34, seated in the screw threaded apertures 35, in the lock bolts 31 and 32. For 85 the purpose of allowing reciprocating movement of the links 30, and the lock bolts 31 and 32 the lock plate 5 is provided with the elongated slots 36.

It will be understood that when the cross 90 head 11 is moved upward by means of the lever 13 there should be no upward movement of the head 23, and in order to prevent this upward movement of the head during the time the springs 18 and 19 are being 95 compressed, the detent or arm 37 is provided which engages, when in a lowered position, the projection 38 formed upon the lock bolt 32 which prevents an end or outward movement of said lock bolt 32. It will 100 also be understood that when the lock bolt 32 is held against endwise movement there can be no rotary or oscillating movement of the disk 28 by reason of the links 30 being 105 coupled to said disk and lock bolt 32. By 110 the movement of the lever 13 in a direction to elevate the cross head 11 the springs 18 and 19 are compressed and held in compression by the bell crank or lever 37 and the projection 38 and there can be no action of 115 the springs 19 until released as hereinafter 120 described.

With the parts just above described and in the position described the door 2 is in condition to be locked as follows: The door 2 125 is properly seated in its opening and rotated in the direction of the arrow, shown in Fig. 5 and until the door has assumed the position illustrated in Fig. 6. By this rotary movement of the door the inclined end of 130

the blade or plate 39 comes in contact with the inner edge 40 of one of the lugs 4^a, said particular lug being located in proper relationship with reference to the beveled ended 5 blade or plate 39. By a continuance of the rotation for a limited distance the sliding bolt 41 will be moved inward by means of the flange or blade 39, which inward movement swings or rocks the lever 42, which lever is held in contact with the nut 43, which nut is located upon the bolt 41; as the lever 42 swings inward, the lever 37 is moved upward, thereby bringing said lever out of engagement with the projection 38, after 10 which the bolts 31 and 32 are moved outward by the action of the springs 19 and their outer ends extended beyond the periphery of the door and into proper sockets or recesses formed in the door jamb. 15 It will be understood that the levers 37 and 42 should be formed integral with each other or securely connected together and pivotally mounted upon the screw 43^a, which screw is attached to the lock plate 5. 20 It will be understood that the blade or plate 39 should be formed integral with the bolt 41 or securely connected thereto, so that the movement of said plate or blade will carry with it the bolt 41. For the purpose of 25 holding the lever 42 in proper contact with the nut 43 or the inner end of the bolt 41, the spring 44 is provided, which spring abuts against the lever 42 and the spring-case 9. After the door has been rotated and 30 the lever 37 brought out of engagement with the projection 38 the head or block 23 is forced upward, which upward movement carries with it the link 27, which link in turn rotates the disk 28 and forces the links 35 30 in an outward direction forcing with them the lock bolts 31 and 32.

It will be understood that after the bolt 41 has been forced in and the door locked the door can not be opened until the lock 45 bolts 31 and 32 are brought inward or their outer ends detached from their sockets.

Upon the spring case 9 is mounted the plate 45, upon which plate is pivotally mounted the trip lever 46, which trip-lever 50 is pivotally mounted intermediate its ends. From the trip-lever 46 is extended the trip-arm 47, as best illustrated in Fig. 10. When the lever 46 is rocked by means of the ordinary and common time lock lever 48, said lever being pivotally mounted upon the time lock case 49 and when rocked in the direction indicated by the arrow (see Fig. 1) the arm 47 is moved downward, thereby disengaging said arm from the trip lever 50, thereby freeing said trip-lever 50, at which time said trip lever 50 is free to swing in the direction of the arrow, adjacent said lever, thereby, releasing the catch lever 51 and permitting the upper end of said catch lever to swing in the direction indicated by

the arrow. As the top or upper end of the catch lever 51 swings as above described its bottom or lower end swings or moves in the opposite direction upon its pivot 51^b, thereby, releasing the lug 52, which lug is carried by the bar 53, which bar is slidably mounted upon the spring case 9 and is carried by the extension 78, which extension is formed integral with the bar 21, but upon the opposite side of the spring housing 9 from which the lug 52 extends from the bridge bar 24. It will be understood that when the lug 52 is brought into an elevated position it will ride upon the inclined edge 55, until it comes opposite the notch 56, at which time the rock bar 57 is elevated, which rock bar on account of its rounded corner 58 and rounded corner 59 of the lug 52 has a tendency to swing the bar 53 toward the catch bar 51 and engage the notch 56, thereby locking the bar 53 in an elevated position. This movement takes place during the time the springs 18 and 19 are brought into compression.

For the purpose of keeping the lug 52 in the recess 56 the rock bar 57 is held in the position illustrated in Fig. 7, by means of the spring 59, which spring abuts against the flange 60 formed upon the rock bar 57, which flange is extended through the curved slot 61 and into the spring aperture or housing 62. When the lug 52 is released from the notch 56 the springs 18 will carry the bar 21 downward by means of the cross head 11, which movement carries with it the head 23 and rocks the disk 28 by means of the link 27, said rocking movement of the disk causes the locking bolts 31 and 32 to move inward and unlock the door, at which time the door is free to be rotated and swung open.

For the purpose of moving the head 23 downward with the bar 21 when the springs 18 are released, the bar 21 is provided with the T-head 22, which T-head carries with it the head 23, thereby causing a rotation of the disk 28 and moving the lock bars inward. For the purpose of normally holding the arm 47 in an elevated position and in position to engage the trip lever 50 the plunger 63 is provided, which plunger presses against the top or upper end of the lever 46, and for the purpose of holding the plunger in such position, the spring 64 is provided, which spring is located around the plunger 63 and in the barrel 65, which barrel is secured to the plate 45 by means of the screws 66.

Through the base plate 5 is located the short shaft 67, upon which shaft is mounted the rock plate 68 which rock plate is provided with the recess 69 and into which recess is seated the bottom or lower end of the lever 46 and when the lever 46 is moved by the time lock lever 48, the rock arm 70

will be moved in the same direction which movement rocks the detent or catch 71 in the position so as to come in contact with the edge of the disk 28 and when the catch 71 is in the position illustrated in Fig. 6 the 5 detent is in position to catch the shoulder 72 and prevent any backward movement of the said disk 28 in the event the springs 19 do not perform their function. It will be 10 understood that the rock arm 70 must be seated in the notch 70^a formed in the detent 71, so as to properly actuate said detent. It will be understood that by providing the 15 detent 71 and the shoulder 72 there can be no rotation of the disk 28 and hence the lock bolts can not be forced inward and the door opened. It will be understood that the detent 71 never goes into service except 20 when the springs 19 do not perform their function and when they do not throw the links 30 over the center. The principal purpose of locking the disk 28 against rotation is to prevent the lock bolts from being moved so as to disengage them from 25 their sockets in the event the safe proper is injured by explosions or other injury.

It is well understood that experienced 30 burglars will sometimes locate the lock bolts by drilling into the side of the safe and when they locate them will move the lock bolts endwise or force the bolts inward, thereby, unlocking the door. For the purpose of over-coming this fault the lock plate 5 is provided with the stop lug 73, which 35 stop lug is so located that one of the links 30 will come in contact with said lug, thereby, preventing the rotation of the disk 28, this feature being best illustrated in Fig. 6. When the link 30 is brought into contact 40 with the stop lug 73 the pivotal point of the link is past or above the common center.

For the purpose of preventing the links 30 from displacement from the pin 33 the overlapping straps 74 are provided, which 45 straps are connected to the lock plate 5 by means of the screws 75 or their equivalents. In some instances burglars attempt to destroy the time locks by a small explosion, thereby permitting the clock or clocks to 50 run down quickly and operate the time lever, thereby releasing the door. In order to prevent the releasing of the lock bolts by reason of a slight explosion the time lock case 49 is set upon a bendable plate or 55 sheet 76 and when pressed in or forced in by the explosion the lug 77, which is formed integral with said plate 76 will come in the path of the pin or lug 78 and prevent any movement of the lock bolts. The bendable 60 plate or sheet 76 is secured to the lock case 49 in any convenient and well known manner and the lock case 49 is carried by the door 2.

For the purpose of preventing the trip 65 lever 50 from swinging too far upon its

pivotal point when released, the spring case 9 is provided with the stop flange 50^a, which is so located that the trip lever 50 will strike said stop flange when the reciprocating bar 53 moves upward. For the purpose of giving 70 a quick movement to the trip lever 50 as the reciprocating bar 53 moves downward said trip lever is provided with the shoulder 51^a the movement being imparted to the trip lever by means of the collar or flange 75 78^a coming in contact with said shoulder 51^a.

Having fully described my invention, what I claim as new and desire to secure by Letters Patent, is—

1. In a bolt operating mechanism for safe 80 doors, the combination of a safe, lock bolts slidably mounted on a safe door, one of said bolts provided with a projection, a bell crank carried by the door adapted for contact with the projection of the lock bolt, a 85 sliding bolt provided with a beveled ended flange adapted for contact with the jamb of the door and to actuate the bolt, a spring adapted to hold the bell crank in position for engagement with the projection on the 90 lock bolt, and springs adapted to actuate the lock bolts in opposite directions, substantially as specified.

2. In a bolt operating mechanism for safe 95 doors, the combination of a safe door, lock bolts slidably mounted on the safe door, a lock plate carried by the door, a disk rotatably mounted upon the lock plate, said disk having pivoted thereto lock bolt actuating links, a sliding bolt provided with a beveled end, said beveled end adapted to actuate the sliding bolt in one direction by the rotation of the safe door, a spring case carried by the safe door, springs located in 100 said case, means for compressing the springs, a time lock lever, mechanism intermediate the time lock lever and the springs adapted to release the springs, said springs thus released adapted to withdraw the lock bolts, substantially as and for the purpose specified. 105

3. In a bolt operating mechanism for safe 110 doors, the combination of a door adapted to be rotated, a lock plate carried by said door, said lock plate mounted upon yielding supports, a spring casing secured to the lock plate, lock bolts slidably mounted on the door, a disk located intermediate the inner ends of the lock bolts, links pivotally connected to the disk and to the lock bolts, respectively, a reciprocating bar mounted in the spring casing, a sliding head mounted upon the reciprocating bar, a link connected to the sliding head and to the disk, a cross head carried by the reciprocating bar, 115 springs adapted to abut against the cross head and the spring casing, a trip lever pivotally mounted intermediate its ends, a trip arm adapted to be actuated by the trip lever, a trip lever adapted for contact with the trip 120 125 130

arm, a catch lever adapted to be released by the trip lever, a reciprocating bar provided with a lug adapted for engagement with the catch lever, said reciprocating bar adapted to be actuated by the trip lever, a reciprocating bar adapted to be actuated by the reciprocating bar having a cross head, and said reciprocating bar provided with a cross head and a T-head, said T-head adapted to move the sliding head downward and

a time lock lever adapted to actuate the trip lever pivoted intermediate its ends, substantially as and for the purpose specified.

In testimony that I claim the above, I have hereunto subscribed my name in the presence of two witnesses.

BARTHolemew F. KLOHS.
